JOHN WESLEY MARDEN AND HARVEY CLAYTON RENTSCHLER, OF EAST ORANGE, NEW JERSEY, ASSIGNORS TO WESTINGHOUSE LAMP COMPANY, A CORPORATION OF PENNSYLVANIA

ULTRA-VIOLET LAMP

Application filed November 21, 1930. Serial No. 497,132.

This invention relates to a lamp for the production of ultra-violet radiation and more particularly to gaseous conduction lamps of the negative glow type having a spectrum 5 relatively rich in ultra-violet radiation of a preferred wave length.

Heretofore in the art ultra-violet radiation has been recognized as being particularly beneficial in therapy and in the promotion of 10 certain bactericidal reactions. Heretofore the greater number of available sources of artificial ultra-violet radiation have been arc devices utilizing carbon, iron, mercury vapor, or tungsten arcs. Such devices while 15 yielding ultra-violet radiation yield such radiation in relatively large quantities which are difficult to control and to apply and which moreover require expensive auxiliary equipment to operate.

20 In copending application Serial No. 437,659 filed March 21, 1930, by J. W. Marden et al., which application is assigned to the same assignee as the present application, there is disclosed a type of ultra-violet radiating 25 device which has been developed particularly for use in living rooms and other enclosed places where a mild source of ultra-violet radiation is desired. The J. W. Marden of this copending application is the same 30 J. W. Marden of the present application.

Briefly stated the ultra-violet radiating device of the above identified copending application comprises a negative glow discharge device of the gaseous conduction type 35 incorporating indirectly heated cathode assemblies and mercury vapor.

The ultra-violet lamp is arranged for use directly from a lighting circuit of 110-220 volts by electrically connecting a plurality 40 of such lamps in series with a suitable ballast resistance, preferably an incandescent lamp of suitable current carrying capacity, to cut down the line voltage to that which operates the glow discharge lamps.

45 The heater element of the cathode assemblies and the thermionically active indirectly heated sleeve members thereof are electrically connected in shunt relation so as to provide means to control the glow discharge of the device.

The combination of glow discharge device and incandescent filament lamp may be assembled in a unit and inserted in an ordinary lamp socket and allowed to burn for prolonged periods of time without the emission 55 of deleterious amounts of ultra-violet radiation. Such a device, for example, set up in an ordinary living room may be operated with substantial safety and with substantial therapeutic benefit to those generally inhabiting the room.

It has been found that certain bactericidal and other actions are materially sensitive to ultra-violet radiation of the shorter wave lengths and in particular to wave lengths 65 approximating 2537 Angstrom. We have found that the ultra-violet lamp of the above identified copending application may be materially improved and made of great value 70 in the application of the lamp for special purposes, such as bactericidal actions, by increasing the relative proportion of ultra-violet radiation of 2537 Angstrom emitted therefrom.

It is one of the objects of the present invention to so improve the glow discharge device of the above identified copending application.

It is another object of the present invention to provide an ultra-violet lamp of the 80 negative glow discharge type having a spectrum relatively rich in ultra-violet radiation approximating 2537 Angstrom.

It is another object of this invention to provide means to limit vapor pressure of 85 the mercury in a gaseous conduction lamp of the negative glow type.

It is another object of this invention to provide an ultra-violet lamp giving a spectrum relatively rich in ultra-violet radiation 90 of approximately 2537 Angstrom.

Another object of this invention is to facilitate the application of ultra-violet radiation in therapy.

A further object of our invention is to provide an ultraviolet lamp whose envelope has at least one portion thereof whose transmission factor to the ultraviolet light generated therein is relatively high.

Other objects and advantages will be ap-

parent as the invention is more fully disclosed.

Heretofore many attempts have been made to obtain ultra-violet radiation that is rich in the 2537 Angstrom line. In general it is found that radiation of this wave length is strongly absorbed by mercury vapor and while a more or less increase in the quantity of radiation of the 2537 wave length radiation has been obtained, the quantity of radiation of other wave lengths has been similarly increased in approximately the same order of magnitude.

In the device of the above identified co-pending application the type of negative glow discharge obtained therein is distinctive over prior art devices in that it is diffused or dispersed throughout the interior of the enclosing envelope rather than being localized at or around the electrode surfaces.

Heretofore arc discharge or gaseous conduction devices of the ultra-violet type have incorporated in addition to the mercury vapor a proportion of an inert or monatomic gas. The higher gas pressure, even though the mercury vapor pressure within the device is maintained low as by water cooling, causes the discharge to concentrate or to localize upon the electrodes. The vapor pressure of the mercury in the region outside of the arc is still sufficient to absorb the greater proportion of the 2537 Angstrom radiation in the discharge.

In the device of the above identified co-pending application the glow discharge being general throughout the enclosing envelope generates the 2537 Angstrom radiation in all parts of the device. This radiation is in part absorbed by the mercury vapor present in the device. We have found, however, that this absorption may be reduced in large measure by limiting the vapor pressure of the mercury to within certain limits (specifically between .001 to .08 m. m. of mercury) and that the ultra-violet radiation thus obtained is relatively rich proportionally in radiation of approximately 2537 Angstrom.

This increase in the 2537 Angstrom radiation is not of the same order of magnitude as the increase in other wave length radiation as is obtained by prior art methods, but is of greater intensity than are the lines of the other wave length radiation and may be as much as ten times as strong as the other wave lengths of ultra-violet radiation. This makes the lamp of particular value as a source of short wave length radiation for special therapeutic purposes.

Before further disclosing the nature and scope of the present invention reference should be made to the accompanying drawing wherein

Fig. 1 illustrates in side elevational view partly in section one type of ultra-violet

radiating gaseous conduction device constructed in accordance with the present invention; and

Fig. 2 illustrates in side elevational view partly in section a smaller type of such device.

Referring to Fig. 1 the gaseous conduction device of the present invention comprises an enclosing envelope 1 having a re-entrant stem 2 of the tipless type through which extend leading-in support wires 3 and 4 from which are supported indirectly heated cathodes 5 and 6, the heater elements 7 and 8 (not shown) of which are electrically connected in series across the leading-in support wires 3 and 4 by means of conductor 9.

Cathodes 5 and 6 are electrically connected to leading-in wires 3 and 4 by means of conductors 10 and 11 respectively. A small amount of mercury 12 is enclosed within the envelope 1. The device is highly evacuated in any suitable manner through tubulature 13 of the stem 2.

The enclosing envelope 1 is preferably comprised of material previous to ultra-violet radiation, such as Corex glass, quartz and the like. Cathodes 5 and 6 may comprise what is known in the art as oxide coated cathodes of the indirectly heated type and may be briefly described as being comprised of a cylindrical sleeve member indicated by numerals 5 and 6 exteriorly surfaced with thermionically active alkaline earth metal compounds 14 and interiorly disposed refractory metal heater elements 7 and 8, preferably of the coil type as illustrated, and also preferably comprised of tungsten.

The sleeve member is provided with end plugs 15 comprised of refractory insulating material, such as alumina, for the purpose of assisting in centrally positioning the heater element and to facilitate the heating up of the sleeve member of the cathode by retaining the heat energy of the heater elements within the sleeve member.

The heater elements 7 and 8 of the cathodes are electrically connected in series and in shunt relation to the cathode sleeve members 5 and 6 so that when a glow discharge passes between said sleeve members the electric current conducted thereacross is by-passed from the current flowing in said heater elements.

The device illustrated in Fig. 2 is substantially identical in constructional details as the device illustrated in Fig. 1 but of smaller size and the enclosing envelope 1 may be comprised of material either pervious or impervious to ultra-violet radiations but having a portion 16 thereof relatively more pervious to ultra-violet radiation than the remainder of the envelope. Portion 16 may comprise, for example, a bulbous thin glass window, such as has heretofore been disclosed in U. S. Patent No. 1,735,302, issued November 11, 1929, to C. M. Slack, which patent is as-

signed to the same assignee as the present invention. As illustrated, the window is of substantially the same composition and is homogeneously united with the major portion of the envelope.

In accordance with the present invention the mercury vapor pressure of the glow discharge device illustrated in Figs. 1 and 2, the constructional features of which have been disclosed and claimed in copending application Serial No. 437,659 above identified, is limited to a range of from .001 to .08 m. m. of mercury.

In order to obtain this we preferably design the device so that the heat radiating capacity of the device is sufficient to maintain the internal temperatures thereof between 20° C. and 75° C. At vapor pressures of mercury above approximately .08 m. m. of mercury the 2537 Angstrom line of ultra-violet radiation is materially absorbed.

In Fig. 1 the device illustrated is of relatively large heat generating capacity, the cathodes being designed to give relatively large amounts of ultra-violet radiation. Accordingly the mercury 12 is collected in a protuberance 17 having a more or less restricted opening 18 within the envelope 1 so that there is a limited exposure of the mercury 12 to the heat energy liberated within the envelope 1 during operation of the device. As the vapor pressure of mercury may rise to .08 m. m. before substantial absorption of the 2537 Angstrom radiation is materially obtained, it is to be appreciated that such a mechanical means, as is herein illustrated for restricting the vaporization of the mercury within the container or of facilitating the radiation of the heat energy of the device so that the internal temperature of the device may be maintained within the desired temperature range, will suffice for the purposes of the present invention.

With greater heat energy input the construction 18 may be made relatively small. With lesser heat energy input the mercury may be left fully exposed to the heat radiation as is illustrated in Fig. 2.

There are many ways of accomplishing or of obtaining this minimum or preferred vapor pressure of mercury or of controlling the internal temperature of the device, but the method herein disclosed appears to be most expedient.

Having broadly and specifically outlined the nature and scope of the present invention and given a specific embodiment thereof it is apparent that there may be many modifications and departures made of the present invention without substantially departing from the nature and scope thereof and such departures and modifications are anticipated as may fall within the scope of the accompanying claims.

What is claimed is:

1. A gaseous conduction device of the glow discharge negative glow type comprising an enclosing vitreous envelope permeable at least in part to ultra-violet radiation, spaced thermionically active electrodes of the indirectly heated type, the heater elements thereof being electrically connected in series, and in electrical parallel relation to the thermionically active elements of said cathodes, and substantially only mercury vapor at pressures ranging from .001 to .08 millimeters of mercury.

2. An ultraviolet lamp of the gaseous-conduction negative-glow type comprising an enclosing envelope, a plurality of electrodes and a gaseous filling, the major portion of said envelope being substantially impervious to ultraviolet radiations and a restricted portion of said envelope being permeable to ultraviolet radiations the restricted portion of said envelope being small as compared to the area of said major portion, the composition of said restricted portion of the said envelope being substantially the same as that of the major portion of the envelope, said restricted portion being homogeneously united to said major portion of the envelope.

3. An ultraviolet lamp of the gaseous-conduction negative-glow type comprising an enclosing envelope, a plurality of electrodes and a gaseous filling, a portion of said envelope being of greater thickness than another portion thereof and substantially impervious to ultraviolet radiations, said other portion thereof being sufficiently thin to be permeable to ultraviolet radiations the composition of said first mentioned portion being substantially the same as that of said other portion, said other portion being homogeneously united with said first mentioned portion.

4. An ultraviolet lamp of the gaseous-conduction negative-glow type comprising an enclosing envelope, a plurality of electrodes and a gaseous filling, said envelope being substantially homogeneous, a portion of said envelope being of a thickness sufficient to prevent ultraviolet radiation from passing therethrough, and a bulbous portion homogeneously united with said other portion, said bulbous portion having at least a portion thereof of sufficient thinness to allow the passage of ultraviolet radiations therethrough, the composition of said first mentioned portion of said envelope and said bulbous portion being substantially the same.

5. An ultraviolet lamp of the gaseous-conduction negative-glow type comprising an enclosing envelope, a plurality of electrodes and a gaseous filling consisting substantially completely of a metal of relatively high vapor pressure, said envelope having a portion thereof substantially impervious to

ultraviolet radiations and another portion thereof permeable to ultraviolet radiations, the area of said second mentioned portion being relatively small as compared to the area of said first mentioned portion, the composition of the second mentioned portion being substantially the same as that of said first mentioned portion, said second mentioned portion being homogeneously united with said first mentioned portion.

6. An ultraviolet lamp of the gaseous conduction negative glow type comprising an enclosing envelope, a plurality of electrodes and a gaseous filling therein, said envelope comprising a major portion and a restriction portion, the area of said major portion being large as compared to the area of said restricted portion, said restricted portion being in the form of a bulbous thin window whose composition is substantially the same as that of said major portion, said restricted portion being homogeneously united with said major portion.

7. An ultraviolet lamp of the gaseous conduction type comprising an enclosing envelope, a plurality of spaced thermionically active cathodes of the indirectly heated type and a gaseous filling therein, the heater elements thereof being electrically connected in series and in electrical parallel relation to the thermionically active elements of said cathodes and substantially only mercury va-

por at a pressure ranging from 0.01 to 0.8 millimeters of mercury, said envelope having a major portion and a restricted portion, the area of said major portion being large as compared to the area of said restricted portion, the composition of said major portion being substantially the same as the composition of said restricted portion, said restricted portion being in the form of a bulbous window whose thickness is relatively small as compared to the thickness of the major portion.

8. An ultraviolet lamp of the gaseous conduction negative glow type comprising an enclosing envelope, a plurality of electrodes and a gaseous filling therein, said envelope comprising a major portion and a restricted portion, the area of said major portion being large as compared to the area of said restricted portion, said restricted portion being in the form of a bulbous thin window whose composition is the same as that of said major portion, said restricted portion being homogeneously united with said major portion and part of said restricted portion being relatively thin as compared to said major portion.

In testimony whereof, we have hereunto subscribed our names this 18th day of November, 1930.
